SHEET-FEEDING MECHANISM.

1,314,359.

Specification of Letters Patent. Patented Aug. 26, 1919.

Application filed March 5, 1918. Serial No. 220,421.

To all whom it may concern:

Be it known that we, HAROLD D. PENNEY, a citizen of the United States, residing at Pelham, in the county of Westchester and State of New York, and GEORGE F. Russ, a citizen of the United States, residing at Jersey City, in the county of Hudson and State of New Jersey, have invented certain new and useful Improvements in Sheet-Feeding Mechanism, of which the following is a specification.

This invention relates in general to means for successively feeding one or more articles such as sheets of paper, or the like, from a pile of such articles.

The invention finds particular adaptation for use with envelop filling machines such as disclosed in the copending application of Harold D. Penney, Charles F. Whiteman, and George F. Russ, filed November 14, 1917, Serial No. 201,950; and the description and claims herein relate in part to matter originally claimed in said application.

Among the main objects of the present invention it is aimed to provide means for effectively picking off one envelop or one circular at a time from a pile and feeding them forward during a certain predetermined interval of time, and properly positioning them as to time and position for proper subsequent coöperation.

A particular feature of the invention is the provision of a feeding element having an active rotary member whereby articles such as envelops, circulars, sheets of paper, or the like, may be successively fed forward in an effective manner.

These and other features, capabilities and advantages of the invention will appear from the subjoined detail description of certain specific embodiments thereof in which—

Figure 1 is a side elevation showing piles of circulars ready to be picked;

Fig. 2 is an enlarged fragmental elevation showing the elements coöperating with the picker in coöperative relation to one another;

Fig. 3 is a fragmental end elevation showing the picker and coöperative parts in coöperative relation;

Fig. 4 is a fragmental plan corresponding somewhat to the illustration of Fig. 2;

Fig. 5 is a fragmental sectional view showing the picker more in detail;

Figs. 6 and 7 are detail, side and end elevations, respectively, of one of the picker 55 rotors;

Fig. 8 is a fragmental section of a modification; and

Fig. 9 is a fragmental plan of the modification shown in Fig. 8. 60

In the form shown in Figs. 2, 3, and 4, a platform 10 is provided for receiving articles, such as envelops, sheets of paper, circulars, or the like, in the course of operation of the machine from the pickers or feeding means forming the main part of the present invention. The platform 10 is merely illustrated to show a suitable means for receiving the articles from pickers and in the present instance has formed thereon and in 70 coöperative relation therewith an abutment plate 11 secured to the bracket 12 mounted on the slide 13 and which travels in the guide-ways 14 formed in the brackets 19. The slide 13 has downwardly extending projections 15 pivotally connected by the links 16 to the levers 17 which are fixed to the shaft 18 journaled in the lower ends of the brackets 19. The shaft 18 has fixed thereon a cam lever 20 which coöperates with the 80 cam 21 fixed to the driving shaft 22. By means of the cam 21, it will be seen that the abutment plate 11 will be intermittently reciprocated, and this will be timed to be actuated after having received one or more articles to further advance the same according to the requirements and setting of the machine. 85

In Fig. 1, the platform just described is concealed from view by the plate 23 from 90 beneath which plate 23 the article or articles received by the platform 10 are discharged into means carried by the conveyer 24 to be further advanced in the course of operation of the machine. 95

The means for successively picking one article at a time and feeding it onto the platform 10 will now be described. There may be one or more of such feeding means to successively feed articles to a receiver such 100 as the receiving platform 10, so that from a plurality of piles of articles, each of a different kind, one from each pile may be fed onto the platform 10 and then such received articles all together advanced in the course 105 of operation of the machine. In Fig. 1, only

two chutes, or magazines 25 and 26, for carrying such piles of articles are provided which may operate together or individually to feed articles onto the platform 10. When 5 one or more such chutes 25 and 26 are set to be operated simultaneously, the feeding of the articles will be preferably timed so that they will alternately feed articles to the platform and thereby insure the proper 10 piling of the articles one above the other when this is desired, and also prevent jamming of the articles when being fed onto the platform 10. The reciprocation of the abutment plate 11 will in such case preferably be timed to operate only after having received an article from each chute. Since 15 the chutes 25 and 26 and the therewith co-operating pickers are substantially identical in construction and operation, it will only be necessary to describe one in detail, to which end the chute 25 will now be described. The articles *a* to be fed forward are arranged in a pile 27 on the chute 25 on edge, that is, with 20 one of their edges engaging the lower surface or floor of the chute 25 and suitable means provided for feeding such pile forward into position to have the articles successively picked from the chute 25. In the present instance, the chute is inclined, there- 25 by affording a gravity feed along the chute 25 which inclination is particularly adapted with the present device to coöperate in other respects hereinafter to be described to further insure the efficient successive feeding of 30 the articles.

In the picking of the articles from the chute 25, there are several elements to contribute more or less materially to the effective operation of the machine, among 40 which may be enumerated the receding end floor portion 28 of the chute 25 and the upper guide-plate 29 from which the articles are fed to loosely mounted guide-disks 30 exteriorly located of the positively actuated rotatable picker members 31, the friction finger 32 which coöperates with the picker members 31 to frictionally retain the succeeding articles from forward movement with the article engaged by the picker 45 members, the outer guide finger 33 and the feed rolls 34 and 35 which coöperate with one another to receive the articles advanced by the picker members 31 to feed the same forward onto the platform 10, the guide finger 33 insuring the proper deflection of the article fed forward by the feed rolls 34 and 35 onto the platform 10.

The present device is particularly adapted for use with flat articles *a*, such as envelopes, circulars, and the like, which have a comparatively small dimension in thickness relative to their width and length, especially their length, and as shown in Figs. 1 and 5, the inclination of the chute 25 relative to the picker members 31 is such

that the articles *a* when in position to be advanced will be inclined with their edges substantially stepped relative to one another, and their faces defined by their widths and lengths substantially horizontal. When 70 it is desired to prevent feeding of the articles from the chute 25, it will only be necessary to pack up the pile of articles *a* beyond the edge 36 of the plate 29 so that the advanced or bottommost article may be 75 propped up against such edge 36.

On the other hand, when it is desired to position the articles for feeding, the articles will be so packed that the advance or bottommost article will have its advance edge 80 resting on the idlers 30 and the succeeding articles backed up in the stepped relation aforesaid. The receding floor portion 28 constituting slanting means being inclined farther downward than the remainder of 85 the floor portion of the chute 25 will operate to relieve the advance articles from the weight of the succeeding articles, it being understood that the stepped relation between the successive articles will appear 90 both at their advance and rear edges, and thereby facilitate retention of the succeeding articles by the friction finger 32 from being advanced with the advance article being engaged by the picker members 31. 95 The plate 29 and the friction finger 32 coöperate with one another to properly align the successive articles in stepped relation, the friction finger 32 being disposed between the picker members 31 and being prefer- 100 ably composed of a resilient material, such as rubber, or the like, will extend down below the upper levels of the picker members 31, thereby to further depress and consequently free the advanced article from 105 the succeeding article to further facilitate the exclusive engagement of the advance article by the picker members 31, the idlers 30 in the meantime affording a support for the sides of the advance article, as well 110 as the succeeding article, and coöoperating to permit the downward deflection of the middle of the advance article as aforesaid.

From the foregoing, it will be seen that one of the essential functions performed 115 by the chute 25, receding floor 28, guide-plate 29, idlers 30 and friction finger 32, is to effectively separate and free the advance article for engagement by the picker members 31 to the exclusion of the succeeding 120 articles. It will also be seen that by this means the refined adjustment so necessary and essential with the ordinary feeds for sheets of paper, or the like, is entirely dispensed with.

The picker members 31 and the idlers 30 are preferably mounted on the same shaft, in the present instance the shaft 37 on which the disk shaped idlers 30 are loosely mounted, and on which the picker 130

members 31 are fixed. The idlers 30 are preferably disposed in alinement with imaginary lines passing adjacent to the inner surfaces of the sides of the chute 25 5 to conveniently receive the articles near their outer lateral edges. The picker means are disposed inwardly of the disks 30 and preferably consist of two disk members, as shown in the present instance, having article 10 engaging means disposed at one portion of their periphery, such as the needles 38. The shaft 37 is driven from a suitable source being connected in the present instance by the bevel gear 39 at one end 15 thereof in mesh with the bevel gear 40 on the driving shaft 41 connected to some suitable source of driving power, not shown. The friction finger 32, the guide-plate 29 and the guide finger 33 are shown mounted 20 on the bracket 42 secured to the chute 25. The guide-plate 29 and friction finger 32 will be adjusted to exercise a retaining action sufficient to prevent the advance of the succeeding articles with the advance article, 25 but not sufficient to hamper in any way the forward movement of the advance article by the picker members 31.

The feed rolls 34 and 35 are so disposed relative to the picker members 31 which 30 are rotating in a direction to draw the advance article over their tops, that the advance article will be fed right in between such feed rolls 34 and 35, and grasped by such feed rolls 34 and 35 to further advance 35 them. The feed rolls 34 and 35 are preferably knurled rolls with a roll 35 adjacent to the outer surface of each idler 30, and a roll 34 in mesh with each of such rolls 35. The positions of the picker members 31 40 and idlers 30 relative to the rolls 35 is preferably such, as shown in Fig. 5, where the peripheries of the picker members 31 and idlers 30 will extend in beyond and between the rolls 35.

45 The rolls 35 are mounted on the shaft 43 which is journaled in the lower ends of the brackets 44, while the rolls 34 are mounted on the shaft 45 which is journaled in the upper ends of the brackets 44 and resiliently 50 maintains the rolls 34 in engagement with the rolls 35 by means of the spring 55 pressed bearing portions 46. One end of the shaft 43 has secured thereto a bevel gear 48 in mesh with the bevel gear 49 which is secured to the driving shaft 50 by means of which such shaft 43 is driven, and the other end of the shaft 43 is provided with a gear 51 in mesh with the gear 52 on the shaft 45 whereby the shafts 43 55 and 45 may be simultaneously driven from the driving shaft 50. The speed of the rolls 34 and 35 relative to the picker members 31 will be such as to effectively grasp and remove the article out of the way of 60 the picker members 31 before the picker 65

engaging means 38 can return into article 70 engaging position. After leaving the rolls 34 and 35, the advance article will preferably be deflected by the finger 33 to discharge onto the platform 10.

As shown in Figs. 6 and 7, the picker disk 31 is preferably formed of two segments 53 and 54 with the needles 38 slidably mounted in orifices formed in the segment 53 which may be secured to the segment 54 by means of the pins 55 formed on the segments 53 and registering with the orifices 56 in the segment 54. The needles 38 are locked in position by the advance screws 57 whereby the needles 38 may be 80 adjusted to extend at various distances to suit the requirements. Each picker 31 is preferably provided with more than one needle 38, in the present instance two needles 38 being shown, one to initiate the feed of 85 the article to be picked, and the other to give such picked article a final forward thrust.

As shown in the modification illustrated in Figs. 8 and 9, the friction finger 58 may extend substantially from one idler 30 to the other. Otherwise the operative parts are substantially the same as the modification illustrated in Figs. 1 to 6, inclusive, except that the article to be fed forward by the 90 picker members instead of being discharged to a platform at a level substantially lower than the discharge level, will be discharged onto the rails 59 substantially at the same level as the discharge level. When an article 95 is grasped by the picker members 31' of the modification of Figs. 8 and 9, it will be fed to the rolls 34' and 35' from which it will be fed to the rails 59 and from the rails 59 between the movable jaw member 60 and the 100 fixed jaw member 61 which is secured to and carried by the conveyer 24', the movable jaw member being pivotally mounted on the fixed jaw member 61. The movable jaw member 60 has an extension 62 to be engaged 105 by the abutment 63 which is disposed in the path of movement of such extension 62, thereby to open the jaw members at a certain distance from the rolls 34' and 35' to receive the article A being fed from such 110 rolls 34' and 35'. The jaw member 60 is also provided with a spring 64 to immediately rock said jaw member 60 into engagement with the article fed forward and thereby between the jaw members 60 and 61, when the conveyer 24' has advanced the jaw members 60 and 61 beyond the abutment 63.

115 The elongated resilient finger 58 it will be seen extends from one idler 30' to the other, and thus resiliently presses each article 120 against said idlers 30', preventing the rotation of such idlers when an article is not being fed while the intermediate portion of the finger 58, having no support at its middle portion, will be deflected downward and 130

thereby deflect the advance edge of the advance article at its intermediate portion into engagement with the picker members 31'.

It will be seen from Fig. 9 that the rolls 34' are mounted on the shaft 65 which has gears 66 at both ends in mesh with the gears 67 mounted on the stub shafts 68 on which the rolls 35' are mounted. For actuating the feed rolls 34' and 35', one of the gears 67 10 is actuated by some suitable source of power not shown.

It is obvious that various changes and modifications may be made to the details of construction without departing from the 15 general spirit of the invention.

We claim:

1. In a machine of the character described, a magazine for holding flat articles by edge engagement, means for advancing 20 said articles with their edges in stepped relation to one another, means for augmenting the stepped relation of the advance articles to facilitate the exclusive engagement of the advance article for withdrawal, and 25 means for engaging the exposed face of the free end of the advance article to advance such advance article.

2. In a machine of the character described, a magazine for holding flat articles 30 by edge engagement at an inclination with their edges in stepped relation to one another, means for deflecting the edges of the advance articles to facilitate the exclusive engagement of the advance article for withdrawal, and means for engaging the exposed face of the free end of the advance article to withdraw such advance article.

3. In a machine of the character described, a magazine for holding flat articles 40 by edge engagement at an inclination with their edges in stepped relation to one another, and means for deflecting the advance edges of the advance articles at the middle to facilitate exclusive engagement of the 45 advance article at such middle portion for withdrawal.

4. In a machine of the character described, a magazine for holding flat articles by edge engagement at an inclination with 50 their edges in stepped relation to one another, means for successively extracting the articles from the magazine and disposed to operate medially of the articles being extracted, and means for deflecting the advance edges of the advance articles at the middle to facilitate the exclusive engagement 55 of the advance article by said extracting means.

5. In a machine of the character described, a magazine for holding flat articles 60 by edge engagement at an inclination with their edges in stepped relation to one another to facilitate the exclusive engagement of the advance article for withdrawal, and 65 rotatable pins for successively engaging the

exposed faces of the free ends of the advance articles to extract them from said magazine.

6. In a machine of the character described, a magazine for holding flat articles 70 by edge engagement at an inclination with their edges in stepped relation to one another to facilitate the exclusive engagement of the advance article for withdrawal, means for successively engaging the exposed 75 faces of the free ends of the advance articles to extract them from said magazine, and means for grasping the article extracted and removing the same out of engagement with the extracting means before the succeeding article is engaged.

7. In a machine of the character described, a magazine for holding flat articles by edge engagement at an inclination with 80 their edges in stepped relation to one another to facilitate the exclusive engagement of the advance article for withdrawal, rotatable pins for successively engaging the exposed faces of the free ends of the advance articles to extract them from said magazine, 85 and means for grasping the article extracted and removing the same out of engagement with the rotatable pins before the succeeding article is extracted.

8. In a machine of the character described, a magazine having a floor for holding a plurality of flat articles on edge and being disposed at an inclination to gravitationally advance said articles, said articles being inclined relative to said floor so that 100 the upper ends of the articles are in advance of their lower ends and their edges are in stepped relation to one another to facilitate the exclusive engagement of the upper end of the advance article for withdrawal.

9. In a machine of the character described, a magazine having a floor for holding a plurality of flat articles by edge engagement and being disposed at an inclination to gravitationally advance said articles, 110 said articles being inclined relative to said floor so that their edges are in stepped relation to one another, and a receding floor portion at the lower end of said floor to relieve the advance articles from the weight 115 of the succeeding articles to facilitate the exclusive engagement of the advance article for withdrawal.

10. In a machine of the character described, a magazine having a floor for holding a plurality of flat articles by engaging their edges and being disposed at an inclination to gravitationally advance said articles, 120 said articles being inclined relative to said floor so that their edges are in stepped relation to one another, disks for supporting the sides of the advance edges of said articles, means for successively extracting said articles operating between said disks, and 125 130

means for deflecting the advance edges of said advance articles medially of said disks to further facilitate the exclusive engagement of the advance article by said extracting means.

11. In a machine of the character described, a magazine having a floor for holding a plurality of flat articles by engaging their edges and being disposed at an inclination to gravitationally advance said articles, said articles being inclined relative to said floor so that their edges are in stepped relation to one another, disks for supporting the sides of the advance edges of said articles, means for successively extracting said articles operating between said disks, and means for deflecting the advance edges of said advance articles medially of said disks to further facilitate the exclusive engagement of the advance article by said extracting means and frictionally retain the succeeding articles from advancement with said advance article.

12. In a machine of the character described, a magazine for holding a plurality of flat articles by edge engagement, means for successively extracting said articles from said magazine, and means for deflecting the advance article at the point of engagement with said extracting means without removing the same from the magazine to facilitate the exclusive engagement of said advance article by said extracting means.

13. In a machine of the character described, a magazine for holding a plurality of flat articles by edge engagement, disks for supporting the sides of the advance edges of said articles, and means disposed between said disks for successively engaging said articles to extract the same from said magazine and including a rotatable disk having a needle projecting from its periphery for engaging the face of the advance article to advance the same.

14. In a machine of the character described, a magazine for holding a plurality of flat articles by edge engagement, disks for supporting the sides of the advance edges of said articles, means disposed between said disks for successively engaging said articles to extract the same from said magazine and including a rotatable disk having a needle projecting from its periphery for engaging the face of the advance article to advance the same, and means for adjusting said needle to suit the requirements.

15. In a machine of the character described, a magazine for holding a plurality of flat articles by edge engagement, and means for successively engaging said articles to extract the same from said magazine and including a rotatable disk embracing a removable segment and a needle adjustably mounted in said segment to project from the periphery of said disk.

16. In a machine of the character described, a magazine for holding a plurality of flat articles by edge engagement, means for successively engaging said articles to extract the same from said magazine and including a rotatable disk embracing a removable segment and a needle mounted in said segment to project from the periphery of said disk, and means for adjusting the extent of said needle to suit the requirements.

17. In a machine of the character described, a magazine for holding a plurality of articles stepped relative to one another, means for supporting the sides of the advance articles, means for successively extracting the articles from said magazine operating medially of said supporting means, and a rubber finger disposed to deflect the advance edges of the advance articles so as to facilitate the exclusive engagement of the advance article by said extracting means and also frictionally retain the succeeding articles from advancement with said advance article.

18. In a machine of the character described, the combination of a magazine for holding flat articles, means for supporting the rear end of the bottommost article, means for supporting the sides of the advance end of the bottommost article, the intermediate part of the advance end of said bottommost article being free of support, and means for engaging the lower face of said intermediate part of the lowermost article for extracting the same.

19. In a machine of the character described, the combination of a magazine for holding flat articles, slanting means for supporting the rear end of the bottommost article, anti-friction means for supporting the advance end of the bottommost article, the intermediate part of said bottommost article being free of support, and means for engaging the lower face of the lowermost article for extracting the same.

20. In a machine of the character described, the combination of a magazine for holding flat articles, means for supporting the rear end of the bottommost article, means for supporting the advance end of the bottommost article, the intermediate part of said bottommost article being free of support, means for engaging the lower face of the lowermost article for extracting the same, and yieldable friction means for retarding the movement of the next to the bottom article as the bottommost article is extracted.

21. In a machine of the character described, the combination of a magazine for holding flat articles, means for supporting the rear end of the bottommost article, means for supporting the advance end of the bottommost article, the intermediate part of said bottommost article being free of sup-

port, means for engaging the lower face of the lowermost article for extracting the same, and means for retarding the movement of the next to the bottom article as the bottommost article is extracted, said retarding means having more adhesion for the articles than the articles do for each other and less than the extracting means have for the articles.

10 22. In a machine of the character described, the combination of a magazine for holding flat articles, means for supporting the rear end of the bottommost article, means for supporting the advance end of the bottommost article, the intermediate part of said bottommost article being free of support, means for engaging the lower face of the lowermost article for extracting the same, and yieldable friction means for retarding the movement of the next to the bottom article as the bottommost article is extracted, said retarding means having more adhesion for the articles than the articles do for each other and less than the extracting means have for the articles.

23. In a machine of the character described, the combination of, a magazine adapted to hold articles of varying thickness, means comprising a picker pin adapted to pull out the endmost article, and yieldable friction means adapted to engage the intermediate part of the next to the endmost article when said endmost article is being drawn out and deflect the intermediate parts of said articles.

24. In a machine of the character described, the combination of, a magazine for holding a plurality of flat articles, means for engaging the sides of the outer flat face of the endmost article, and yieldable means for engaging the intermediate part of the endmost articles, deflecting such part and holding in place the next to the endmost article as the endmost article is being drawn out.

25. In a machine of the character described, the combination of, a magazine for

holding a plurality of flat articles, means for engaging the sides of the outer flat face of the endmost article, and yieldable means for engaging the intermediate part of the endmost articles, deflecting such part and holding in place the next to the endmost article as the endmost article is being drawn out, said yieldable means affording more resistance to the movement of the articles than do the articles upon each other and less resistance to the movement of the article than the removing means exerts upon the article.

26. In a machine of the character described, the combination of, a magazine slanting toward its discharge end and adapted to hold flat articles therein in approximately horizontal position with the rear end of the article resting against the magazine, rotatable disks supporting the advance end of the lowermost article, revolving picker pins adapted to engage the lowermost article and pull the same out of the magazine, and a yieldable friction block adapted to engage the advance ends of a plurality of said lowermost articles for retarding all of said articles except the lowermost as said lowermost article is extracted by the pins.

27. In a machine of the character described, the combination of, a magazine adapted to hold and support flat articles at their rear ends, means for supporting the advance end of the lowermost article, means comprising a picker pin adapted to engage the intermediate part of the lower face of the advance end of the lowermost article and extract it from the magazine, and a yieldable friction means adapted to engage and hold the next to the lowermost article as said lowermost article is drawn out by the picker pin and deflect the intermediate part of said articles.
